TOY CATAPULT

George Virneburg, New York, N. Y.

Application March 29, 1934, Serial No. 717,965

4 Claims. (Cl. 124—2)

This invention relates generally to toys and refers more particularly to a toy catapult for shooting arrows, balls or other equivalent projectiles.

The invention broadly aims to provide a toy catapult which is so constructed and arranged that it may be optionally used in a variety of different ways in order to catapult a number of different types of projectiles therefrom.

The invention further comprehends a toy catapult embodying a handle having means carried by one end thereof which defines a projectile guide and which also affords an anchorage for an elastic sling so as to provide the same with a bight portion for engaging the projectile to catapult the same from the device while engaged by the guide.

More particularly the invention contemplates a toy catapult engaging a frame having a handle and divergent portions of the frame formed respectively with aligned projectile guides together with an elastic sling anchored to the frame in such a manner as to produce a bight for engaging the projectile and which sling, when tensioned, is adapted to catapult the projectile through the guides.

The invention further provides a toy catapult including a continuous frame constituting respectively a sight opening and an opening through which a projectile is adapted to be catapulted, together with an elastic sling and means on the frame for anchoring the sling so as to dispose the same in spanning relation thereto.

Other objects of the invention reside in the provision of a device of the indicated character which is comparatively simple in its construction, inexpensive to produce and which provides a highly amusing and attractive toy.

With the above enumerated and other objects in view, reference is now made to the following specification and accompanying drawing in which there has been disclosed, by way of example, several preferred embodiments of the invention, while the claims cover other variations and modifications thereof which fall within the scope of the invention.

In the drawing:

Fig. 1 is a perspective view illustrating the catapult in use and position for shooting a round shafted projectile or arrow.

Fig. 2 is a similar view showing the device equipped with another type of sling for catapulting a ball.

Fig. 3 is a perspective view of a slightly modified form of the invention illustrating the same

employed for shooting a flat shafted projectile or arrow.

Fig. 4 is a similar view showing a further modification of the type of sling used and illustrating in full and broken lines several ways in which the sling may be used in connection with the frame.

Referring to the drawing by characters of reference, the catapult includes a frame member which is designated generally by the reference character A and which, in the forms of the invention shown in Figs. 1, 2 and 4, includes a continuous frame body 10 which is of generally circular formation but which, within the scope of the invention, may be of any other desired configuration to define a central opening 11, the axis of which opening extends through the thickness of the frame body. The frame member also includes a handle 12 which extends radially and preferably in use depends therefrom. The frame body is provided with a plurality of projectile guide means which are designed for selective use with a variety of projectiles of different types such as, for instance, the round shafted arrow B shown in Fig. 1, or the flat shafted arrow C shown in Fig. 3, the guide means for the former being in the form of a substantially semi-circular notch 13 which is disposed in a plane coincident with a plane passing through the handle and which guide notch has its axis parallel to the axis 10 of the opening 11, with the notch opening through the inner periphery of the frame body 10. Another guide means consists of aligned elongated openings 14 which extend through diametrically opposite portions of the frame body 10 and the axes of which are preferably disposed perpendicular to a plane passing through the handle 12.

The frame body 10 is provided with a plurality of means for anchoring elastic slings thereto for the purpose of catapulting the projectiles and which slings may be of various types such as illustrated in Figs. 1, 2, 3 and 4, by the reference characters D, E and F. The means for anchoring the sling for catapulting the projectile B while engaged in the guide notch 13, consists of a pair of hooks 15 which are disposed at spaced points on the outer periphery of the frame body 10 in a plane substantially in alignment with the guide notch 13. The means for anchoring the sling for catapulting a projectile of the type C shown in Fig. 3, consists of pairs of clips 16 and 17 secured to opposite faces of the frame body 10 with the pairs located respectively adjacent each guide opening 14. As illustrated, the clips di- 55

verge from their anchored ends towards their free ends so that the sling is wedged securely into its anchored relation thereto.

As particularly disclosed in Fig. 1 of the drawing, the device is employed for the purpose of catapulting a round shafted arrow designated by the reference character B which arrow has a head 18 and a notched rear terminal 19. The sling D as shown in Figs. 1 and 3 is of a braided elastic type having knots 20 at its opposite ends which engage with the hooks 15 to properly anchor the sling in place. In use in this form of the invention, the opening 11 serves as a sight opening for aiming the projectile at the target.

In the form of the invention illustrated in Fig. 2, the sling E is of a flat ribbon type with knots 21 at its opposite ends and in this form the knotted ends 21 are engaged respectively with one clip of each pair of clips 16 and 17 so that the sling 20 is disposed in spanning relation to the frame body 10 and the bight portion 22 has secured thereto a projectile seat 23 which is especially designed to accommodate a ball or spherical projectile which is catapulted through the opening 11 and which is also employed as a sight for aiming the projectile at a target.

In the form of the invention illustrated in Fig. 3, the frame member which is identified generally by the reference character G includes a body of a non-continuous type providing divergent furcations or arms 24 and 25 connected with the handle 26 and except for the fact that the body in this form is non-continuous the same is identical with the frames of the other form of the invention.

Where it is desired to use a sling in the form of a continuous elastic band as illustrated at F in Fig. 4, it is essential when using the same for shooting a projectile, while guided by the guide notch 13 of the frame member, to dispose the anchored portion in a non-interfering relation to the guide 13 and the projectile which is guided thereby, hence the handle 12 is provided with a stud 27 which is arranged below the guide notch 13 and with which the anchored portion of the sling is engaged as clearly illustrated in Fig. 4. Furthermore, where the form F of the sling is to be used for catapulting a projectile while guided by the guide openings 14, the sling may be engaged transversely around the frame body 10 and seated in the pairs of clips 16 and 17 as

shown in broken lines. Obviously, if the sling of the type 21F is used for catapulting a ball or spherical projectile through the opening 11 in the manner shown in Fig. 2, the unused anchored portion of the elastic band, after being engaged with one clip of each pair of clips 16 and 17 is engaged under the stud 27.

From the foregoing it will be apparent that a toy catapult has been devised which is capable of use in various ways for catapulting projectiles of varying types, while employing slings of different constructions.

What is claimed is:

1. A toy catapult including a handle, a frame carried by the handle having upwardly extending divergent portions, aligned projectile guides formed respectively in said divergent portions and disposed substantially equidistantly forwardly and rearwardly of the handle, an elastic sling anchored to the frame on opposite sides of one of the divergent portions and having a bight engageable with a projectile and operable when the sling is tensioned to catapult the projectile through the guides. 15

2. A toy catapult including a handle and a continuous frame defining a combined sight and projectile opening and having a notch in the inner edge located in alignment with the handle and constituting a projectile guide, an elastic band, and means on the frame for anchoring the band thereto so as to dispose the rear portion of the same in spanning relation to the notched portion of the frame and the forward portion of the band in an out of the way position below said notched portion of the frame. 30

3. A toy catapult comprising a frame having a plurality of projectile guide means for optional use, an elastic sling, and a plurality of means for anchoring the sling to the frame for selectively projecting a projectile from the frame while engaging one of said guide means. 35

4. A toy catapult comprising a frame having a plurality of guide means for optionally shooting a projectile from the frame in the line 45 of its axis or perpendicular thereto, an elastic sling, and a plurality of means for anchoring the sling to the frame for selectively catapulting the projectile from the frame while engaging one of said guide means. 50

GEORGE VIRNEBURG.
